UNITED STATES PATENT OFFICE.

FRANK A. BROWNE, OF WAYNE, PENNSYLVANIA, ASSIGNOR TO THE BARBER ASPHALT COMPANY, OF PHILADELPHIA, PENNSYLVANIA, A CORPORATION OF WEST VIRGINIA.

PUMPING MACHINERY.

Application filed August 14, 1922. Serial No. 581,718.

This invention relates to pumping machinery and more particularly to machinery for pumping materials which are extremely viscous or solid at ordinary temperatures and which require heating in order to promote a fluent condition, such for instance as Trinidad asphalt, refined asphalt, asphalt cements and the like. Such materials often contain mineral matter, the presence of which together with the normally solid or viscous condition of the material renders the act of transferal by pumping an extremely difficult one attended constantly by numerous hazards.

An object of the invention is to provide a new and improved pump designed particularly to maintain a fluent condition in the material to be transferred, to provide automatic valves of an extremely simple nature which will operate with a minimum amount of wear on the parts, and to permit the facile dissembling of the parts for the purpose of cleaning or repair.

These and other objects are accomplished by what I now regard as the preferred form of my invention from among numerous other possible forms and arrangements embraced within the spirit of the invention and the scope of the appended claims.

In the accompanying drawings, Fig. I is a view in top plan of a pump constructed in accordance with the present invention; and

Fig. II is a view of the pump in side elevation, illustrating the pumping cylinder and valve chest in longitudinal section.

With reference to the drawings 10 indicates a bed frame supporting at one end a cylinder 11 disposed in a horizontal position having one end open and its interior bored adjacent its opposite end to provide a displacement chamber 12 affording a slight clearance around the plunger when the latter is at the end of its instroke. The inner end of the cylinder is reduced in diameter and provided with an integral intake and delivery connection in the nature of a vertically disposed cylinder 13 bored uniformly to provide a vertical chamber. The interior of the cylinder 13 is subdivided by an annular transverse internal ledge 14 into a pair of superposed valve chambers 15 and 16, the former constituting the outlet valve chamber and the latter the inlet valve chamber. A

valve cage 17 is arranged in each valve chamber, and comprises an annular base 17^a which rests upon an annular member 18 constituting a valve seat. The member 18 associated with the upper valve cage rests upon the ledge 14 and that of the lower cage 17^b rests upon the flange 19 of a steam jacketed elbow 20 which is applied to the lower open end of the cylinder 13. The cages are inserted into the bore from opposite ends, their positions being limited primarily by the ledge 14. The valve cage in each instance includes intersecting arch members 21 which confine spherical or ball valves 22 and 23 for controlling respectively the outlet and inlet ports of the valve chambers 15 and 16. The spherical valves 22, 23 normally rest by gravity upon the annular seats 18, closing their openings but are displaced by the forcible introduction and discharge of material through said seats. The valve seats 18, 18 it will be seen, are located directly at either side of the opening through which the pump chamber 12 communicates with the interior of the cylinder 13. The lower valve cage is held in place as previously stated by the application of the elbow 20, while the upper valve cage is held in place by the application to the upper end of the cylinder 13 of the flanged end 24 of a steam jacketed discharge pipe 25.

The open end of the cylinder 11 is recessed internally to provide an annular packing cavity 26. Between the cavity 26 and the chamber 12 is an annular internal ridge 27 constituting the only area of contact between a plunger 28 which operates in the displacement chamber 12 and the internal surface of the cylinder 11. A compression ring 29 is seated within the outer end of the cavity 26 and is forced into the cavity to compress the packing around the plunger 28 by means of bolts 30 which penetrate an apertured flange 31 forming part of the compression ring 29 and which enter appropriately threaded recesses formed in the end wall of the cylinder 11. The plunger 28 is preferably of uniform diameter throughout to facilitate cleaning and is formed with a rounded inner end.

The walls of the displacement cylinder 11 are sufficiently thick to permit the formation therein of annular intercommunicating spaces 32 which serve for the introduction

of steam to maintain the walls of said cylinder at a temperature sufficient to insure a constant fluent condition in the material to be pumped. In a similar manner the walls 5 of the cylinder enclosing the packing 26 are provided with an annular space 33 designed to be steam supplied so as to maintain the packing at an elevated temperature. The walls of the valve cylinder 13 are similarly 10 supplied with interspaces 34 assuring the maintenance of a high temperature therewithin. Thus, it will be seen, the plunger packing, the valve chamber, and the entire 15 pump chamber including its reduced connection to the valve chamber are jacketed for heating. If desired the wall of the valve cylinder 13 may be perforated at points adjacent the valve chambers as at 35 to permit access to the interior for the purpose of 20 adjusting the valves, the apertures being normally closed by removable plugs.

The plunger 28 may be reciprocated in any manner desired, one example being illustrated in the form of a steam cylinder 36 25 suitably mounted on the bed frame 10 and containing a piston which is connected to said plunger through the medium of the piston rod 37. The plunger 28 may however be motor driven or shifted in any other manner 30 as the present invention is not concerned with the specific pump operating means but rather to the pump itself.

Through repeated oscillation of the plunger 28 the heated fluent material is 35 drawn through elbow 20 past the inlet valve 23 unseating the same at each intake stroke, filling the interior of the chamber 12. The material in the chamber 12 is subsequently 40 displaced at each discharge stroke of the plunger 28 and forced through the valve chamber 15 unseating the valve 22 and discharging through the pipe 25.

Owing to the extremely simple nature of the intake and outlet valves it will be seen 45 that the possibility of damage to the parts or failure of operation is reduced to a minimum. In view of the fact that the walls enclosing all of the working parts are maintained at a high temperature by circulating 50 steam the possibility of damage to the pumping mechanism as a whole is minimized, and the chilling of the material is avoided in the event that operation of the pump should cease for any reason. The heating of the 55 packing is effective to prevent adhesion of the asphalt or other material to the packing which would occur if the material were chilled in contact with the packing. By

eliminating contact between the plunger and the cylinder walls as much as possible and 60 accomplishing the transferal of the material by mere displacement instead of by complete reduction of cylinder space as with a tightly fitting piston, possibility of the plunger sticking is prevented and the smooth working 65 of the plunger is assured.

Thus, it will be seen that I have devised a novel form of pump in which the essential elements have been reduced to a high degree of simplicity and are maintained at an 70 elevated temperature, with a view to insuring constant operation of the pump under varying conditions, to reducing wear and to permitting easy dismantling, as well as to securing other advantages which will be apparent to those familiar with this art. While I have illustrated the principle of my invention in connection with a pump of the single action plunger type it will be apparent that the same principles may be embodied in machines of other types such as double acting cylinder and piston pumps and the like, and hence I do not wish to limit myself to the exact construction shown.

Having thus described my invention, I 80 claim:

1. A reciprocating pump for asphalt and the like embodying a pump chamber, intake and delivery valves, a heating jacket for said pump chamber and intake and delivery 90 valves, and means for also heating the packing of the operating member.

2. A plunger pump for asphalt and the like embodying a plunger chamber, intake and delivery connections; and a heating 95 jacket surrounding said plunger chamber, the plunger packing, and the intake and delivery valve connections.

3. A pump for asphalt and the like comprising a reciprocating plunger and a pump 10 chamber surrounding said plunger with clearance, when the plunger is at the end of its instroke; an intake and delivery valve chamber extending across the end of the pump chamber and communicating therewith; intake and delivery valve seats in said valve chamber directly at either side of the opening into the pump chamber, with valves for said seats; and a heating jacket for said 11 pump and valve chambers and their intercommunication, and also for the plunger packing.

In testimony whereof, I have hereunto signed my name at Philadelphia, Pennsylvania, this 5th day of August, 1922.

FRANK A. BROWNE.
